(57) **CLAIM**

The ornamental design for a liquid preparing device, as shown and described.

DESCRIPTION

FIG. 1 illustrates a perspective view of a liquid preparing device, showing my new design;

FIG. 2 illustrates a top view thereof;

FIG. 3 illustrates a bottom view thereof;

FIG. 4 illustrates a left view thereof;

FIG. 5 illustrates a right view thereof;

FIG. 6 illustrates a front view thereof;

FIG. 7 illustrates a rear view thereof;

FIG. 8 illustrates an enlarged partial view of the area indicated by dot-dash-dot-dash line VIII of FIG. 6; and, FIG. 9 illustrates an enlarged partial view of the area indicated by dot-dash-dot-dash line IX of FIG. 7.

The broken dash-dot lines indicate portions of the liquid preparing device that form no part of the claimed design. The broken dot-dash-dot-dash lines illustrate reference lines highlighting areas enlarged in the enlarged partial views or unclaimed surface contours and form no part of the claimed design. None of the broken lines form part of the claimed design.
